OR D 5,395

No. 8-395-

Nov. 28, 1871

UNITED STATES PATENT OFFICE.

ROBERT SCORER AND ROBERT HAM, OF TROY, NEW YORK, ASSIGNOR TO J. L. MOTT, OF NEW YORK CITY.

DESIGN FOR A PARLOR-STOVE.

Specification forming part of Design No. 5,395, dated November 28, 1871.

To all whom it may concern:

Be it known that we, ROBERT SCORER and ROBERT HAM, each of the city of Troy, in the county of Rensselaer and State of New York, have jointly invented and produced a new Design for Parlor-Stoves, of which the following is a specification, reference being had to the accompanying photograph, in which—

Figure 1 is a front view of the main body and lower portion and of the top part of a stove which shows our said design. In this stove, as generally constructed, the top part, which in Fig. 1 is shown resting at the line $z z$ directly upon the illuminated section, is separated therefrom by an intermediate section of cast or sheet metal. Fig. 2 is a top view of the upper part of the same stove with the urn removed. Fig. 3 is a separate view of one of the legs of the stove.

Like parts are marked by the same letters in the different figures.

One part of our invention is the design of the urn A, as shown in Fig. 1 of the photograph. Another part of our invention is the design for the swinging cover or plate B, as distinguished by the central ornamented part c, border-molding d, and intermediate surface e, substantially as shown in the photograph, with or without the ornamentation f. Another part of our ornamental design consists of the word "Sirius," composed of letters shaped and arranged together in an arc of a circle upon a plate of a stove, and so as to appear ornamental thereon, substantially as represented in Fig. 2 of the photograph. Another part of our invention is the design for the plate J, as shown in Fig. 1. Another part of our invention is the design for the ring-plate K, as shown in Fig. 1. Another part of our invention is the design for the frame or frames L around the illuminating openings, as represented in the illustration. Another part of our invention is the design for the ring-plate M, as shown in Fig. 1 of the photograph. Another part of our invention is the contour of the fire-pot casing N, as distinguished by having an oval or elliptical

outline in horizontal section, and its sides bounded in vertical section by reverse curves o p q r, as indicated in Fig. 1, irrespective of any ornamentation thereon. Another part of our invention is the compound system of ornaments s t u v shaped and combined on the casing N, as shown in the photograph. Another part of our invention is the design for the base plate W, as distinguished by the ornamental moldings x and y, shaped and arranged as represented in the illustration. Another part of our invention is the design for the removable ash-pit cover Z, as shown in the photograph. Another part of our invention is the design for the foot or leg Y, as represented in Fig. 3. Another part of our invention is the word "Sirius," cast on or with and forming a part of a plate of a stove, essentially as shown in Fig. 3.

What we claim as our invention is—

1. The design for the urn A, as described.
2. The design for the cover B, as described.
3. The design for the top plate G, as set forth.
4. The design for the plate J, as described.
5. The design for the rim-plate K, as described.
6. The design for the frame or frames L, as set forth.
7. The design for the rim-plate M, as shown.
8. The contour of the fire-pot casing N, as set forth.
9. The combination of ornaments on the casing N, as described.
10. The design for the base plate W, as set forth.
11. The design for the ash-pit cover Z, as described.
12. The design for the leg Y, as shown.
13. The word "Sirius," composed of letters shaped and arranged together upon and forming a part of the ornamental design of a plate of a stove, as herein set forth.

ROBERT SCORER.

Witnesses: ROBERT HAM.
